ZEPHER J. BRICONNIER, OF SAN FRANCISCO, CALIFORNIA, ASSIGNOR OF ONE-HALF
TO MAX COHN, OF SAN FRANCISCO, CALIFORNIA.

BLOTTER ATTACHMENT FOR FOUNTAIN PENS.

1,418,696.

Specification of Letters Patent. Patented June 6, 1922.

Application filed November 24, 1920. Serial No. 426,196.

To all whom it may concern:

Be it known that I, ZEPHER J. BRICONNIER, a citizen of the United States, residing in the city and county of San Francisco and 5 State of California, have invented new and useful Improvements in Blotter Attachments for Fountain Pens, of which the following is a specification.

This invention relates to a blotter attachment for fountain pens, and more particularly to a blotter attachment for the cap of 10 a fountain pen.

General objects of the invention are: that the blotter can be easily manipulated when used; that the attachment be simple, and inexpensive to manufacture; and that the attachment is neat in appearance.

It is also an object of the present invention that the blotter be detachable and easily 20 renewable.

Other objects will later appear.

The invention is illustrated by way of example in the accompanying drawings, in which—

25 Fig. 1 is a side elevation of a fountain pen showing my invention incorporated.

Fig. 2 is a longitudinal, central, vertical section of the fountain pen cap and showing the blotter partly unrolled.

30 Fig. 3 is a vertical sectional view on the line 3—3, of Fig. 2.

Fig. 4 is a detail view of the spindle upon which the blotter is wound.

Referring to the drawings more particularly, 10 indicates the ordinary stock or handle of a fountain pen, and 11 the cap or sleeve for enclosing the pen point. The cap or sleeve 11 in this instance is open at each end and its outer end is provided with 15 threads adapted to receive the interiorly threaded cap 12. Through the cap 12 there extends a sleeve 12' in which there is inserted a spindle 13. A collar 14 is secured to the sleeve 12'. The sleeve and spindle extend 20 into a tubular member 13' and the inner end of the spindle is threaded into an intermediate transverse wall of the member 13'. The spindle is free to turn in the sleeve 12'; the collar 14 holding the member 13' and sleeve 25 12' in their positions. The spindle is threaded on its outer end to receive a knurled nut 15 by which the spindle may be turned and in turn rotating the member 13'; the sleeve 12' acting as a guide for the member 13'

and holding it against any lateral movement.

From the collar 14 to the inner end of the spindle, a portion of the spindle's periphery is flattened as indicated at 16, and at the inner end of this flattened portion there is pivotally secured, as at 16', one end of a resilient strip 17. The strip is adapted to swing in a plane corresponding to its flat surface, and beneath it is held one end of a blotter strip 18. The blotter otherwise extends 65 through a longitudinally extending slot 19 in the cap or sleeve 11. The slot terminates at its one end with the outer end of the cap 11, as shown in Fig. 2. The outer end of the blotter 18 extends through a slot 20 in a tubular member 21, and is disposed about the inner surface of said tubular member. A pin 22 is inserted in this tubular formation of the blotter end and binds the same against being withdrawn. The tubular member 21 70 is preferably of hard rubber in order to give the required binding action to hold the blotter.

When it is desired to renew the blotter, the cap 12 is unscrewed, which action will 80 draw with it the spindle 16 and blotter carried thereby; the blotter sliding through the slot 19. After the cap is entirely unscrewed the spindle, cap and blotter can be entirely withdrawn from the cap or sleeve 11. The 85 member 17 is then swung on its pivot 16 and the inner end of the blotter released. The pin 22 can then be withdrawn and the other end of the blotter drawn from the tubular member 21. A new blotter can then be substituted by a reverse operation.

In operation when it is desired to use the blotter, it is only necessary to pull on the tubular member 21 and thus unwind the blotter. This can be accomplished by one 95 hand if desired, which is done by holding the cap or sleeve 11 in one hand and by the use of the thumb and middle finger pushing outwardly on the tubular member. This manner of operation is of course only resorted to when two hands cannot be conveniently used. When the blotting has been accomplished the blotter may then be quickly rewound on the spindle by the operator turning the spindle in the required direction by 100 means of the knurled nut 15.

While I have shown the preferred form of my invention, it will be understood that va-

rious changes in the combination, construction, and arrangement may be made by those skilled in the art without departing from the spirit of the invention as claimed.

5 Having thus described my invention, what I claim and desire to secure by Letters Patent is—

1. A blotter attachment of the character described comprising in combination a fountain pen cap having both ends open, a cap threaded on the outer end thereof, a spindle journalled in said cap and extending into the fountain pen cap, a resilient strip having one end pivotally secured on the spindle 10 and free to be swung so that it is disposed in alignment with the inner portion of the spindle, a blotter strip having one end held between said resilient strip and spindle and extending through a slot formed longitudinally of the cap and extending from the outer end of the fountain pen cap to a point approximately even with the inner end of the spindle.

2. A blotter attachment of the character described comprising in combination a fountain pen cap having both ends open, a cap threaded on the outer end thereof, a spindle journalled in said cap and extending into the fountain pen cap, said spindle being 25 entirely supported by the cap, a blotter strip having one end detachably secured to the spindle and extending through a slot formed longitudinally of the fountain pen cap, and a tubular member detachably secured to the other end of the blotter strip.

3. A blotter attachment of the character described comprising in combination a fountain pen cap having both ends open, a cap threaded on the outer end thereof, a spindle journalled in said cap and extending into the fountain pen cap, a resilient strip having one end pivotally secured on the spindle and free to be swung so that it is disposed in alignment with the inner portion of the spindle, a blotter strip having one end held between said resilient strip and spindle and extending through a slot formed longitudinally of the cap and extending from the outer end of the fountain pen cap to a point 45 approximately even with the inner end of

the spindle, and a tubular member detachably secured to the other end of the blotter.

4. A blotter attachment of the character described comprising in combination a fountain pen cap having both ends open, a cap 50 threaded on the outer end thereof, a spindle journalled in said cap and extending into the fountain pen cap, carrying an enlarged tubular member on its inner end, a sleeve about said spindle extending into said tubular member, a knurled nut threaded on the outer end of the spindle, a blotter strip having one end attached to the tubular member on the spindle, and extending through a slot formed longitudinally of the fountain pen cap, and terminating in the outer end of said fountain pen cap. 55

5. In a device of the character described a support, a sleeve secured in said support, a spindle extending through the sleeve and turnable therein, a roller secured on the outer end of the spindle, said roller being hollow to enclose a portion of the spindle and the sleeve in which the spindle is turnable, a blotter carried by the roller, and 70 means on the roller for securing one end of the blotter. 75

6. In a device of the character described a cap, a sleeve secured in said cap, a spindle extending through the sleeve and the cap 80 and journalled in the sleeve, means on one end of the spindle for imparting a turning movement thereto, a cylinder secured to the opposite end of the spindle, said cylinder enclosing that portion of the sleeve and the 85 spindle which projects within the cap, and means for attaching one end of a blotter to the cylinder.

7. In a device of the character described, a stationary sleeve, a cylinder supported 90 thereby and journalled thereon, means extending through the sleeve and secured to the cylinder for imparting a turning movement to the cylinder, a blotter adapted to be rolled about and supported by the cylinder, means for attaching one end of the blotter to the cylinder, and means for securing the cylinder and the spindle against endwise movement. 95

ZEPHER J. BRICONNIER
